UNITED STATES PATENT OFFICE.

FRANKLIN E. WARBURTON, OF PAWTUCKET, RHODE ISLAND.

DESIGN FOR A THREAD-PACKAGE.

SPECIFICATION forming part of Design No. 32,431, dated April 3, 1900.

Application filed May 23, 1899. Serial No. 717,962. Term of patent 14 years.

To all whom it may concern:

Be it known that I, FRANKLIN ELLSWORTH WARBURTON, a citizen of the United States, residing at Pawtucket, Providence county, 5 State of Rhode Island, have invented and produced a new Design for Thread-Packages, of which the following is a specification.

In the accompanying drawings, Figure 1 is a perspective view of my new design for a 10 thread-package, and Fig. 2 is an edge view thereof.

The essential features of the new design consist in a thread-package of cylindrical shape the outer peripheral surface of which 15 is divided by a diagonal line into two sections, each of which is made up of parallel diagonal stripes alternating in contrasting colors, the parallel stripes of the respective sections forming an angle to each other, and 20 the ends of the package having irregularly-disposed curved short stripes of contrasting colors.

Thus, referring to the drawings, A is the

central cylindrical portion of the thread-package, and B the threads thereon, and on the 25 peripheral surface of the package the threads are divided by a diagonal line *b* into two sections C and D, each of which is made up of parallel diagonal stripes *c c'* and *d d'* in contrasting colors, and the parallel stripes of the 30 two sections C and D form an angle, as at *e*, to each other. The ends of the package have irregularly-disposed curved short stripes F G of contrasting colors surrounding the plain central cylindrical portion A. 35

What I claim is—

The design for a thread-package substantially as described and illustrated in the accompanying drawings.

In testimony whereof I have signed my 40 name to this specification in the presence of two subscribing witnesses.

FRANKLIN E. WARBURTON.
